CLAIM

The ornamental design for a fishing rod leash, as shown and described.

DESCRIPTION

FIG. 1 is a perspective view of the fishing rod leash showing my new design, the broken line showing of environment being for illustrative purposes only and forming no part of the claimed design;

FIG. 2 is a front elevational view thereof.

FIG. 3 is a rear elevational view thereof.

FIG. 4 is a right side elevational view thereof, the left side view being a mirror image of the right side view.

FIG. 5 is a top plan view thereof; and,

FIG. 6 is a bottom plan view thereof.
